PRACTICE DRUM

Donald L. Banta, Terre Haute, Ind.

Application June 19, 1945, Serial No. 600,276

3 Claims. (Cl. 84—411)

1

The present invention relates to new and useful improvements in practice drums designed to be used by persons learning to play a drum, and has for its primary object to combine therewith means for carrying the drumsticks, whereby a combined practice drum and carrying case is provided.

A further object of the invention is to provide a practice drum constructed in the form of a pair of discs hingedly connected to each other at one edge, together with means for supporting the upper disc in an open inclined position and providing a cushion on the upper surface thereof for use in practicing the playing of a drum.

A further object of the invention is to provide a practice drum of this character in which the hingedly connected discs form a carrying case in which the drumsticks may be conveniently carried.

A further object of the invention is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully described hereinafter and claimed, reference being had to the accompanying drawing forming part hereof, wherein like numerals refer to like parts throughout, and in which:

Figure 1 is a side elevational view.

Figure 2 is a vertical sectional view.

Figure 3 is a plan view of the case with the upper disc or cover removed.

Figure 4 is a sectional view taken substantially on a line 4—4 of Figure 2.

Figure 5 is an enlarged fragmentary sectional view of the connection for a sectional drumstick.

Referring now to the drawing in detail, wherein for the purpose of illustration I have disclosed a preferred embodiment of the invention, the numeral 5 designates the practice drum generally which comprises upper and lower discs 6 and 7, the lower disc constituting the bottom of a carrying case, while the upper disc 6 constitutes the lid therefor which is hingedly connected at one edge, as indicated at 8, to one edge of the lower disc 7, whereby the upper disc may swing upwardly at its free edge relative to the lower disc.

The surface of the lower disc 7 is recessed to form a compartment 9 within which a pair of sectional drumsticks 10 are adapted to be carried, one section of the drumsticks being provided with a threaded socket 12, while the other section of the

2

drumstick is formed with a threaded stud 11 for threaded engagement in the socket to secure the sections of the drumstick in assembled relation, as indicated in Figure 5 of the drawing.

5 The compartment 9 is formed with recessed lateral extensions 13 in which a pair of fins or props 14 are adapted for positioning, the props or fins being hingedly connected in the bottom of the recess 9 by means of hinge members 15 attached to one longitudinal edge of the props. The other longitudinal edges of the props are inclined as indicated at 16 and adapted for swinging upwardly into an upstanding position, as shown to advantage in Figure 4 of the drawing for supporting the lid 6 in an inclined position. The inclined edges 16 of the props are provided with lugs 17 adapted to enter recesses 18 in the under side of the lid 6 to secure the props against accidental downwardly folding position.

10 20 To the under side of lid 6 is also attached one end of a chain or other flexible member 19 having a coil spring 20 attached to its lower end and secured in the recess 9 of the bottom section 7 of the case, the chain 19 limiting the opening movement of the lid 6 and the spring 20 exerting a downward pulling force on the lid when the latter is in its open position to maintain the same tightly on the upper edges of the props 14.

25 30 The lid 6 is provided with a spring catch 21 adapted for engaging a detent 22 carried by the bottom section 7 to secure the lid in its closed position when the props 14 are folded downwardly in the extension 13 of the recess 9 in the manner as indicated in Figure 3 of the drawing.

35 35 The top of the lid 6 is provided with a rubber or other resilient pad 23 which may thus be used as a practice pad by a drummer.

40 45 From the foregoing it will be apparent that when the lid 6 is secured in its raised position, the device may be used as a practice drum and when the lid is closed, the device may be used as a carrying case for the drumsticks.

It is believed the details of construction, manner of operation and advantages of the device 45 will be readily understood from the foregoing without further detailed explanation.

50 While I have herein illustrated and described a preferred embodiment of the invention, it will be apparent that various changes may be made in construction without departing from the spirit of the invention, or from the scope of the appended claims.

Having thus described the invention, what I claim is:

1. In a practice drum, including a drum pad,

a disc providing mounting means for said pad, and a base substantially coextensive with said disc and hingedly connected thereto, the improvement comprising said base having an upper surface in underlying relation to said disc, a pair of laterally-spaced props, means hingedly connecting said props to said upper surface of said base for swinging movement to and from elevated and folded positions, said props being adapted in said elevated positions to support said disc and pad in an elevated position, said upper surface of said base being formed with a recess therein for seating and concealing said props in said folded position, and spring means connecting said disc and base together and operative to resiliently lock said disc and props in said elevated positions.

2. In a practice drum, including a drum pad, a disc providing mounting means for said pad, and a base substantially coextensive with said disc and hingedly connected thereto, the improvement comprising said base having an upper surface in underlying relation to said disc, a pair of laterally-spaced props, means hingedly connecting said props to said upper surface of said base for swinging movement to and from elevated and folded positions, said props being adapted in said elevated positions to support said disc and pad in an elevated position, said upper surface of said base being formed with a recess therein for seating and concealing said props in said folded position, said props and disc being formed with interfitting pin-and-socket means adapted for interfitting engagement to retain said props in said elevated position, and means including a coil spring connecting said disc and base together and resiliently locking said disc and props in said elevated positions.

3. In a practice drum, including a drum pad, a disc providing mounting means for said pad, and a base substantially coextensive with said disc and hingedly connected thereto, the improvement comprising a pair of laterally-spaced props, means hingedly connecting said props to said base for swinging movement to and from elevated and folded positions, said props being adapted in said elevated positions to support said disc and pad in an elevated position, said base being formed with a recess therein for seating said props in said folded position, said props and disc being formed with interfitting means adapted for interfitting engagement to position said props in said elevated position, means including a coil spring connecting said disc and base together and resiliently locking said disc and props in said elevated positions, and said recess including laterally-spaced prop-receiving portions and an intermediate portion adapted to receive drum sticks therein.
